UNITED STATES PATENT OFFICE.

ALBERT COWELL, OF KIDDERMINSTER, ENGLAND.

DESIGN FOR A CARPET-PATTERN.

Specification forming part of Design No. 5,885, dated June 4, 1872.

To all whom it may concern:

Be it known that I, ALBERT COWELL, of Kidderminster, Worcestershire, in England, have invented a new and original Design for Carpets; and I do hereby declare that the following is a full, clear, and exact description thereof, which will enable others skilled in the art to make and use the same, reference being had to the accompanying photographic illustration forming part of the specification.

The nature of my invention is fully represented in the accompanying photographic illustration, to which reference is made.

This invention relates to a new design for a narrow carpet, to be used on stairs, for rugs, mats, or similar purposes. The design consists of ornamental borders at both sides of the carpet, and of foliate scrolls as a groundwork. The borders are provided with inwardly-projecting tufts. The main scrolls between them are fully illustrated in the photograph.

I claim as my invention—

The design for carpets, as shown.
